(57) **CLAIM**

The ornamental design for an earhook for earpieces, as shown and described.

DESCRIPTION

FIG. 1 is a front elevational view of an earhook for earpieces;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view of the earhook assembled to an earpiece;

FIG. 8 is a front perspective view of the earhook separated from the earpiece;

FIG. 9 is a rear perspective view of the earhook to the earpiece; and,

FIG. 10 is a rear perspective view of the earhook separated from the earpiece.

The broken line showing of the environment is for illustrative purposes only and forms no part of the claimed design.
